Primary Examiner—Wallace R. Burke*Assistant Examiner*—Lisa Lichtenstein*Attorney, Agent, or Firm*—Bernhard Kreten**[57] CLAIM**

The ornamental design for a resistive water heater element, as shown and described.

DESCRIPTION

FIG. 1 is a side view of a resistive water heater element showing my new design, wherein both sides of the resistive water heater element are the same;

FIG. 2 is a top view thereof;

FIG. 3 is a bottom view thereof; and,

FIG. 4 is a perspective view in the intended environment.

The broken-line showing of environmental structure in FIG. 4 is for illustrative purposes only and forms no part of the claimed design.
